Michael D. Mann & Stephen Standward
Letters Patent Dated January 7, 1831.

The inventors referred to in their Letters Patent, and making
part of the same, containing a description on the words of the
said Michael D. Mann and Stephen Standward, themselves of
their improvement in the machine for casting printing type, call-
ed a Vertical Type Caster, which invention they have assigned
to Elizur White of the City of New York, which assignment is
recorded in the Patent Office in the Book of Assignments Page
345.

To all to whom these presents shall come, Be it known that
Ms. Michael D. Mann and Stephen Standward, Mechanicks,
of the City, County and State of New York, have jointly inven-
ted, constructed, and applied to use a new and useful machine,
for casting Printing Type not before known, which we call
the Vertical Type Caster. .... A description of the construction
and manner of using said machine, is correctly set forth, by the
accompanying drawings, and specification, on the words fol-
lowing to wit.

(A) In drawing Fig. 1 represents the long of a table on which
the machine is planted. (BB) Rivets, on which a metal bed piece,
marked (C), is secured (D), A movable metal platform being
immediately over bed piece (C), resting on the words of four
levelling screws, more fixed to the bed (C) by mort and bolt
in the middle.

(E) Side pools cast on, or secured to the platform (C), (G) A shaft
centered at each end resting and turning on centers, which are
fixed in the heads of the pools (E, F). On this shaft is secured
the fixed arm (H), and the swivel joint which holds in center the
movable arm (I). Above the middle of said shaft is fixed the

arm (3). Below the shaft (5), rises the shaft (6), fitted to revolve on journals, the bows of which are formed on the side plates (7, 8). To this shaft is attached the crank (9), the small wheel (10), and an elliptical eccentric arm (11), to the two projecting arms of which at A, is secured an elliptical rim of iron, so as to form round arm (12), an elliptical groove, or channel. From the platform (13), rises the shaft (14), to which is living by a joint and pin, one end of the lever (15). A piston, marked (16), is coupled by a pin and joint, to the other end of said lever, and likewise to the end of arm (11). From the lever (15), projects within the elliptical groove, a pin having on it a friction roller (17), round which travels the aforesaid elliptical rim. On the post (18), is secured a fixed socket, marked (19) through which passes a pin formed on the end of the emptying rod (20). The other end of this rod passes through a fixed socket formed in a projection on the side of arm (2), and is prevented from being drawn out of the socket, by a nut on the end of it (21). An iron reservoir, or metal cante, the bottom and sides of which are enclosed by iron, iron fire place, marked (22), having a grate for the fuel, a door on one side, and a smoke pipe (23), the whole supported on legs, fastened on the base of the table.

1455, side plates to an iron yallow frame, the feet of which are secured by screws to the rim of the reservoir, the cross piece lying directly over it, in a piece of iron secured on the top of this cross piece, a socket is made through which passes the upper end of a piston, or pump rod marked (24), through said rod a mortice is cut at (25), through which passes the lever (26), one end of which is secured by a pin at (27) to an arm and curved projecting end from front (28) of the gallows frame.

From the platform (13), rises a shaft (29), fitted at the upper end to receive the lever (26), in which it is secured by a pin. The lever (26), and (29), are coupled together by the rod (30), having

u joint and pins at each end of it, at one end of the lever (11), is fitted a friction roller, resting against the small wheel (14). In the end of the arm (1), a socket of about three inches deep, and one of one inch diameter is bored. (17) A bit of iron about one inch square, at one end of which a shaft of three inches long is bored, and is slid into the before named socket; this piece so fitted we call a slide arm. It is held to its place by the thumb screw (17). To the iron (11) and the slide arm (17) we make and attach a set of stamp hooks, see fig (18). To each back plate of a common type mould we screw a piece of iron, of the length of said plate, and of a band 1/8, by one inch square, in the upper and under sides of which a groove is formed to receive the handle, of the above size (8.8.8.8). By means of these clamped, and the lever (1), one half of the mould in which the type are to be cast, is secured to the arm (11), and the other half to the slide arm (17), (10) A bent lever having its fulcrum at (11), and working over a pin (15). Its use is to lever or raise one end of the matrix, before discharging the type from the mould. (14). A spring, one end of which is to rest on the matrix, and keeps it to its place, when the type is cast. The other end is secured to the arm (11), (15) A spiral spring by which the piston rod is forced downwards, (16) A nut against which the spring rests. This nut works on a screw formed on the piston rod, and by this nut and screw the force of the pump can be regulated.

fig 18 is section showing the iron forming of our receiver or metal kettle. So the upright column (a.a) which is cast to, and rises above the bottom of the kettle, the chamber (C) is formed, which the passage (d) leads through the lateral projection (e), also cast on the bottom of said kettle. This passage connects with and has its outlet through the passage (f), formed in the projection (f), cast on the inner side of the kettle, in the chamber (C) is fitted the piston, (g) bored through the center

rod (5). It will also be seen that by the depressing one end of the lever (2) the piston rod (V), will be lifted, and that a further turn of the snail, will allow the lever (2) again to rise from the joint of the snail, and the piston to settle down, which it will instantly do, from the action of the spiral spring (15); the fall of the piston will draw a jet of metal up through the spout onto the mould. A still further turn of the snail, again depresses lever (2), and lifts the piston, and also raises the mould from the snail, by means of the lever (2), cam (14), and elliptical ring.

As the mould rises, the rod (5), will cause it to open, and the opening of the mould, will bring the typpet in contact with a hook or hooks (see 13) placed in one or both of the arms (23) as may be found expedient, by which it will be discharged from the mould. But we are not alone confined to the before described manner of forming and hanging the swinging arm (1) of our machine. As to the before described form of the shaft (6), or mode of giving motion thereto, by making shaft (6), in the form of a crop, and a ring at one end of arm (1), sucking this arm to swing on contact, passing through the ring into the arms of the snail (see VV), and in the place of hanging the shaft (6) on centers as before described, we make it to turn on journals formed at the top of the side posts (22, 22') and passing shaft (6) through said posts direct. By under shaft (6), (see VV) we dispense with the cam (14), the elliptic ring, the snail (2), lever (2) and arm (1), before described, and placed on the end of shaft (6) the compound curved snail (3), and between two friction rollers on said snail, we place the curved end of lever (2) the other end being secured to the end of shaft (6) so that by turning the snail (3) and shaft (6) we give the same motion to the shaft (6), and the arms thereto attached, as before described. The compound snail (3) can be shipped or unshipped from the lever (2) by sliding the shaft (6) backwards or forwards in it.

sockets, the small wheel (M) being made wide to prevent the unshipping of
lance (L) (M) a dog for holding shaft (K) in its place.

Summary of what we claim and specify as our inventions and improvements in the above described machine, namely, First. The particular construction of the above described kettle, so as to admit of working the metal directly over the rim, and of taking the metal out of the kettle through a spout rising above said rim. Secondly. The rolling spout and corresponding counter seat by which the form of the spout is adjusted with requisite exactness to the face of the mould, to prevent the escape of metal when ejected into the mould.

Thirdly. The mode of casting by a perpendicular jet of metal, emitted from the metal kettle into the mould, through a spout rising above the rim of the kettle.

Fourthly. The construction and mode of fixing the two arms of the machine, to which the type mould is attached, and the mode of working the type mould, when secured to the ends of said arms.

Fifthly. The application of clamps to a grooved brick piece, on the back of the mould, for holding the mould to the arms of the machine as before described.

Sixthly. The mode of opening and closing the mould by means of the rod (S) and the locket (R) as before described.

Eleventhly. And we further claim as our invention and improvement the above described new arrangement and combination of different parts of the whole machine, by which a great improvement is obtained, in casting printed types.

We testimony that the above is a true specification of our said above named invention, we have hereunto set our hands this 22nd day of December in the year of our Lord one thousand eight hundred and thirty

and thirty
